UNITED STATES PATENT OFFICE.

CLINTON O. HARRINGTON, OF CHICAGO, ILLINOIS, ASSIGNOR TO ALDOBILT COMPANY,
OF CHICAGO, ILLINOIS, A CORPORATION OF ILLINOIS.

LANTERN.

Application filed November 21, 1921. Serial No. 516,837.

These improvements will probably find their most useful application in connection with signal lanterns, for instance such as are used on the railway right-of-way and at 5 highway crossings, but will be found of advantage wherever an unusually great spread of light in particular directions is desired.

In railway signal practice a signal lantern may be positioned in the vicinity of a curve 10 and, according to the forms of lanterns heretofore used and now currently being employed, the axis of the light projection is usually directed toward some intermediate point on the curve so that the engineer may 15 have the effect of the signal throughout as much lateral range as the spread of light from the source permits. Such lanterns do not, however, provide a materially great spread except where special projecting lenses 20 are employed or where an unusually large source of light is used. In such special cases the objection exists of the increased cost of the special construction, the increased cost of maintenance, or both. Furthermore, such 25 practice brings into the system special constructions at only special places, resulting in much unnecessary inconveniences. Among such special constructions are frosted lamps and frosted lenses for spreading the light 30 and also a projecting lens provided on its outer surface with a plurality of parallel ribs.

The principal object of the present invention is to provide simple, easily operated and 35 highly efficient means associated with a source of light and its projecting lens for providing a spread of light which is relatively great, and thus improve the efficiency of the signal. A more specific object is to 40 provide such advantageous means in a form which may be applied to lanterns now in use, with the said desired results. Another specific object is to provide such means in a form which may be readily removable and 45 replaced from time to time as desired, and by removal of the light-spreading means provide for the effective and convenient focusing of the lamp with respect to the lens and of the lantern as a whole with respect 50 to the area desired to be illuminated. Another specific object is to provide a form of light-spreading device in which interchangeability may be had to effect a greater or less spread according to the particular situation. 55 Another object is to provide a light-spread-

ing device which may be positioned for operative use without any focusing operation and without a modification of the adjustments of the lantern parts previously made. It is also an object to provide a device which is 60 of low cost and which may be cheaply and easily installed. Other objects and advantages will appear hereinafter.

In the accompanying drawings, which form a part of this specification, Figure 1 65 is a vertical sectional view, as on the line 1—1 of Fig. 2, of a railway signal lantern of conventional form having a screen device constituting a specific embodiment of a particular feature of novelty as an element or 70 as a device in its operative position; Fig. 2 is a horizontal sectional view of the same device, as on the line 2—2 of Fig. 1; Fig. 3 is a sectional view as on the line 3—3 of Fig. 1; Fig. 4 is an enlarged fragmentary 75 view illustrating the effect of the screen device and lens in refracting the rays of light; Fig. 5 is a fragmentary view of a part of Fig. 4 on an enlarged scale; Fig. 6 is an enlarged fragmentary sectional view showing a 80 modified form of screen; Fig. 7 is a fragmentary enlarged face view of another modified form of screen; and Fig. 8 is a fragmentary section on the line 8—8 of Fig. 7.

The lantern body 10, the projecting lens 85 11 and the source of light 12 mounted on a base 13 are to be understood as being of the usual or of any preferred construction. The source of light 12 is to be understood as being at or substantially at the focus of the 90 lens 11. Ordinarily the lamp is mounted for adjustment in several directions so that the filament at 12 may be conveniently brought to the focal point.

The specific feature of improvement is the 95 provision of a screen as 14 between the source of light and the projecting lens. It is not new to provide some form of screen between the lens and the lamp, and I am aware that colored screens and screens 100 adapted to dim the light have been so positioned. The present screen device as 14 is of a different construction, however, and accomplishes a different result.

The specific screen 14 is a transparent element and may be considered a small rectangular plate of glass having a plurality of vertical ribs 15 (Figs. 4 and 5) thereon.

The plate 14 is readily removably held in 105 a vertical frame 16 having a bottom cleat 110

17, a pair of lateral cleats 18 and a top cleat 19, each cleat being formed to overlie the glass and hold it upon the frame 16. Should it be desired to remove the plate as 14 the 5 top cleat 19 is removed, as by removing the small screw 20 holding it in place, whereupon the plate may be lifted out of the guideways formed by the bottom and lateral cleats, and thereupon the lantern may be 10 used without the screen in such positions as do not particularly call for it, and, importantly, the focusing of the lamp with respect to the lens may then be conveniently performed. Any suitable bracket for holding 15 the screen may be employed.

The effect of the screen as 14 may well be noted from Figs. 4 and 5, in which the source of light 12 is diagrammatically indicated as a point. The parallel ribs 15 will 20 ordinarily be vertical as shown in Figs. 2 and 3 since in railway signal work at least it will ordinarily be desired to spread the rays in the sidewise or lateral directions. When it is desired to spread the light in up 25 and down directions the screen or plate 14 may be turned so that the ribs 15 will extend in the horizontal directions, the plate 14 being square and fitting the carrying frame in either position.

30 Each of the ribs 15 is a very small cylindrical lens. While the number of these lenses may vary to a considerable extent it is preferable to provide a relatively large number of them side by side in order to obtain the desired uniform diffusion of light. The effect of these small lenses is to bend 35 the rays coming from the source 12 so that as the lantern is viewed from in front the light appears to emanate from a plurality of sources as 12^a, 12^b and 12^c in a line, there being a large number of such apparent 40 sources of light from one side of the field to the other.

Without the screen in position the rays 45 from the true source 12 diverge in straight lines to the lens 11. With the screen as 14 in place some of the rays diverge from the source to the lens in substantially the normal way while for the most part they are 50 bent from the true normal line of divergence, the result being that from each of the projections 15 there is a multitude of diverging rays striking the lens, and these rays depart from the lens in a multitude of 55 diverging directions. So far as the divergence of the rays is concerned the effect is that of many independent sources of light.

Turning to Fig. 6 the plate 23 has a plurality of parallel rib-like projections 24 also 60 constituting lenses. These ribs are shown as having a concave surface thereby bending the rays divergently. The ribs 24 may be inclined in one direction only, as illustrated, 65 instead of being symmetrical with respect to the optical axis of the lens, in which case

the light will be diffused chiefly to one side instead of to both sides of that axis. A ray of light from the source striking a portion of a rib 24 which is parallel to the back of the plate 23 will pass through the rib with its direction unchanged. Rays of light falling on an inclined surface of the rib will have their direction changed in a greater or less degree depending upon the angle between the face of the rib and the back of the plate. With such a construction the optical axis of the lantern may be directed at a distant point on a railway curve, and with lateral diffusion taking place principally on one side of the axis the light from 70 the lens will be diverted so as to cover the portions of the curve nearer to the lantern as desired.

If it should be desired to spread the rays in all directions instead of merely horizontally or vertically a lens screen device such as shown, for example, in Figs. 7 and 8 may be employed, in which case the plate 26 is provided on one surface with a plurality of small spherical lenses 27, the effect of which 80 is to cause the rays to emanate from the screen to the lens as though there were an individual source of light at a multitude of points as viewed from in front of the lens, with a consequent wide spreading of the rays 85 in all directions.

While the forms of lens screens specifically illustrated are highly efficient for the purposes indicated, the invention is not limited to the specific characters of the particular screen elements illustrated herein, and reference should be had to the appended claims to determine the scope of the improvements herein set forth.

I claim:

1. In a signal lantern, the combination of a projecting lens, a source of light for projecting rays therethrough, and a substantially transparent plate between the lens and the source of light, said plate having light-refracting means for giving the rays emanating from the lens a materially greater increase of spread in given directions.

2. In a signal lantern, the combination of a projecting lens, a source of light for projecting rays therethrough, and light-refracting means between the lens and the source of light comprising a substantially transparent plate on one surface of which are a plurality of relatively small light-dispersing elements for giving the rays emanating from the lens a materially greater increase of spread in given directions.

3. In a signal lantern, the combination of a projecting lens, a source of light for projecting light therethrough, and light-refracting means between the lens and the source of light comprising a substantially transparent plate on one surface of which are a plurality of relatively long and narrow light-dispers-

ing projections for giving the rays emanating from the lens a materially greater increase of spread in given directions than in other directions.

4. In a signal lantern, the combination of a projecting lens adapted to project rays of light from an associated source in a substantially circular path in cross view, a source of light for projecting light through the lens, and light-refracting means between the lens and the source of light comprising a substantially transparent plate on one surface of which are a plurality of relatively long and narrow substantially straight and parallel light-dispersing projections adapted to increase the spread of light in given directions whereby the light rays from the source de-

fine a path of light which is elongated in cross view.

5. In a railway signal lantern of the character described, the combination of a projecting lens, a concentrated source of light substantially at the focus of the lens, and light-refracting means between the source of light and the lens, and materially spaced from each thereof, for giving the rays emanating from the lens a materially greater increase of spread in given directions.

6. The combination of claim 5 hereof in which said light-refracting means are in the form of a substantially transparent plate having light-dispersing elements thereon.

CLINTON O. HARRINGTON.
